(57) **CLAIM**

The ornamental design for a vehicle tail light, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front, top, left side perspective view of a vehicle tail light showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a front perspective view thereof, mounted on a rear portion of a vehicle, with the rest of the vehicle shown in yellow de-emphasized and half-tone portions so as to illustrate environmental structure. These portions form no part of the claimed design.

The portion painted in yellow in the drawings show portions of the vehicle tail light that form no part of the claimed design.
